R. E. MOYER,
BALING PRESS,
APPLICATION FILED FEB. 16, 1917.

1,261,051.

Patented Apr. 2, 1918.

By Watson E. Coleman

Attorney.

UNITED STATES PATENT OFFICE.

RALPH E. MOYER, OF SCOTTVILLE, MICHIGAN.

BALING-PRESS.

1,261,051.

Specification of Letters Patent. Patented Apr. 2, 1918.

Application filed February 16, 1917. Serial No. 149,044.

To all whom it may concern:

Be it known that I, RALPH E. MOYER, a citizen of the United States, residing at Scottville, in the county of Mason and State of Michigan, have invented certain new and useful Improvements in Baling-Presses, of which the following is a specification, reference being had to the accompanying drawings.

10 This invention relates to certain improvements in baling presses and has relation more particularly to a press of this general character especially designed and adapted for use in connection with hay and straw; 15 and it is an object of the invention to provide a baling press with novel and improved means whereby the material after being compressed within the baling chamber is effectively held against return within the 20 hopper or feeding chamber.

The invention also has for an object to provide a novel and improved holding means positioned adjacent the entrance of a baling chamber and which is constantly urged in a direction toward the chamber in order to prevent return to the hopper of the material compressed after the plunger has been retracted and wherein said means is so constructed as to afford no obstruction 25 to the strokes of the plunger.

The invention consists in the details of construction and in the combination and arrangement of the several parts of my improved baling press whereby certain important advantages are attained and the device is rendered simpler, less expensive and otherwise more convenient and advantageous for use, all as will be hereinafter more fully set forth.

40 The novel features of the invention will hereinafter be definitely claimed.

In order that my invention may be the better understood, I will now proceed to describe the same with reference to the accompanying drawings, wherein—

Figure 1 is a fragmentary view in vertical section illustrating an embodiment of my invention; and

Fig. 2 is a view partly in transverse section and partly in elevation of my invention as herein embodied.

As disclosed in the accompanying drawings, B denotes the baling chamber of a press having an entrance end in communication with the hopper H and the hopper is adapted to be traversed by a plunger P

for compressing within the chamber B the material, such as hay and straw, deposited within the hopper H.

Disposed transversely of the press across the top of the hopper H and immediately adjacent the entrance end of the chamber B, is a bar 1. The bar 1 extends beyond the opposite sides of the press and has secured to each of its extended portions a depending eye bolt 2 with which is connected a retractile member 3 herein disclosed as a conventional coil spring which extends in substantially a perpendicular path. The lower end of the spring 3 is secured to a clip or clevis 4 threaded upon the upstanding rod 5 secured at its lower end, as indicated at 6, to the adjacent side of the press. By rotating the clip or clevis 4 it will be at once self-evident that the tension of the spring 3 may be readily regulated.

As is thought to be self-evident the springs 3 serve to constantly urge the bar 1 downwardly. The bar 1 has secured thereto the rearwardly directed arms 6 having their outer ends pivotally engaged with the rod 7 disposed transversely of the press at the top thereof and at a predetermined point rearwardly of the entrance end of the chamber B.

Secured to the under face of the bar 1 is a body 8 formed preferably of wood and which fits snugly between the side walls of the hopper H and has its bottom 9 formed of metal and disposed transversely on a predetermined downward incline with a portion thereof extending beneath the top wall of the entrance end of the chamber B, whereby the upward movement of the body 8 is limited.

As herein disclosed, the body 8 is secured to the bar 1 through the medium of the upwardly directed headed bolts 10 which are also directed through the arms 6 whereby said bolts 10 also serve to secure said arm 6 to the bar 1. Coacting with the upper portions of the bolts 10 are the clamping nuts 11 for a purpose which is believed to be self-evident. The bottom 9 is also braced by the upwardly and rearwardly directed headed bolts 12 disposed through the forward marginal portion of the bottom plate 9 and through the rear wall 14 of the body 8, the inner or rear portions of said bolts 12 having coacting therewith the clamping nuts 15 as is believed to be clearly shown in Fig. 1 of the accompanying drawings.

It is thought to be self-evident that the curvature of the bottom plate 9 of the body 8 readily permits the material such as hay or straw together with the plunger P to pass therebeneath upon the compression stroke of the plunger as the body 8 will readily rise or elevate. When the plunger P is retracted the springs 3 will serve to force the bottom plate 9 downwardly, whereby the material, under the compression within the chamber B, will be effectively held against outward movement.

From the foregoing description, it is thought to be obvious that a baling press constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my in-

vention in practice, except as hereinafter claimed.

I claim:

In combination with a baling chamber of a press, a body positioned adjacent the entrance of the baling chamber, a bar secured to the top of the body and extending beyond opposite sides of the press and coacting therewith to limit the inward movement of the body, arms secured to the upper face of the body and pivotally engaged with the press at a point inwardly of the entrance to the baling chamber, a plate secured to the inner face of the body, a portion of said plate extending within the entrance for contact with a wall of said entrance for limiting the outward movement of the body, and retractile members coacting with the extended portions of the bar for constantly urging the body inwardly.

In testimony whereof I hereunto affix my signature in the presence of two witnesses.

RALPH E. MOYER.

Witnesses:

EUNICE MOYER,
JOHN C. MOYER.
